CLAIM

The ornamental design for an injectable power port, as shown and described.

DESCRIPTION

FIG. 1 is a perspective view of a first embodiment, lined for color, of an injectable power port.

FIG. 2 is a top view, lined for color, of the injectable power port illustrated in FIG. 1;

FIG. 3 is a bottom view, lined for color, of the injectable power port illustrated in FIG. 1;

FIG. 4 is a front elevation view, lined for color, of the injectable power port illustrated in FIG. 1;

FIG. 5 is a right side elevation view, lined for color, of the injectable power port illustrated in FIG. 1;

FIG. 6 is a rear elevation view, lined for color, of the injectable power port illustrated in FIG. 1;

FIG. 7 is a perspective view of a second embodiment, lined for color, of an injectable power port.

FIG. 8 is a top view, lined for color, of the injectable power port illustrated in FIG. 7;

FIG. 9 is a bottom view, lined for color, of the injectable power port illustrated in FIG. 7;

FIG. 10 is a front elevation view, lined for color, of the injectable power port illustrated in FIG. 7;

FIG. 11 is a right side elevation view, lined for color, of the injectable power port illustrated in FIG. 7;

FIG. 12 is a rear elevation view, lined for color, of the injectable power port illustrated in FIG. 7;

FIG. 13 is a perspective view of a third embodiment, lined for color, of an injectable power port.

FIG. 14 is a top view, lined for color, of the injectable power port illustrated in FIG. 13;

FIG. 15 is a bottom view, lined for color, of the injectable power port illustrated in FIG. 13;

FIG. 16 is a front elevation view, lined for color, of the injectable power port illustrated in FIG. 13;

FIG. 17 is a right side elevation view, lined for color, of the injectable power port illustrated in FIG. 13; and,

FIG. 18 is a rear elevation view, lined for color, of the injectable power port illustrated in FIG. 13.
